UNITED STATES PATENT OFFICE.

SALVATORE QUENTIN LUPO, OF NEW YORK, N. Y.

COMBINED VANITY COMPACT AND CIGARETTE CASE.

Application filed April 1, 1925. Serial No. 19,910.

This invention relates generally to the class of carrying receptacles and has particular reference to a combined vanity compact and cigarette case for ladies.

One of the principal objects of the present invention is to provide a light, compact and attractive carrying case for cigarettes and cosmetics which is adapted to be suspended from the arm of the wearer and in which the suspension means is attached to the closure cap for one of the compartments so that when the cover is removed, the same will be suspended by the suspension means to give the wearer free use of the hands to hold the body of the case with one and to remove the contents thereof with the other.

The invention furthermore comprehends a combined carrying case of the character set forth which is so shaped and designed as to facilitate the holding of the case and one of the removable sections thereof conveniently in one of the hands while permitting free use of the other hand to remove and apply the contents thereof.

As a still further object the invention resides in the provision of a combined carrying case which is comparatively simple in its construction, inexpensive to manufacture and highly efficient in its purpose.

With the above recited and other objects in view, reference is had to the following specification and drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Figure 1 is a perspective view of the combined vanity compact and cigarette case closed.

Fig. 2 is a similar view illustrating the manner of using the same as a vanity case.

Fig. 3 is a similar view illustrating the manner in which the cigarettes are removed from their compartment.

Fig. 4 is an enlarged vertical sectional view through the same.

Referring to the drawings by characters of reference 10 designates a substantially cylindrical body which is provided with an open upper end defined by a reduced externally threaded portion 11. The case body 10 is provided with a bottom wall 12 hav-

ing a recess 13 thereunder and a reduced externally threaded depending boss 14. A closure cap 15 having an interiorly threaded lower end 16 is removably mounted on the upper end of the body 10 to define together therewith a cigarette containing compartment 17 and the top wall of said cap has attached thereto a looped suspension element 18 which is adapted to suspend the same from the arm of the wearer. A removable bottom section or cap 19 having an interiorly threaded upper end 20 is connected with the body 10 and defines a compartment 21 which is designed to receive and contain a compact 22 and an applicator or puff 23. A mirror 24 is secured within the recess 13 and an ornamental tassel 25 is secured to the bottom wall of the removable lower cap or section 19 to depend therefrom. The tassel 25 supports and conceals within the strands thereof a cosmetic pencil 26.

In use of the device as a vanity case, the wearer unscrews the lower cap or compartment 19 and holds the body with the upper cap 15 applied between the thumb and first two fingers of the hand as illustrated in Fig. 2 without removing the suspension element 18 from the wrist. The removed lower cap or compartment is supported between the remaining two fingers and heel of the hand as also illustrated in Fig. 2, thereby permitting the wearer free use of the other hand for applying the contents with the applicator 23. When it is desired to remove the cigarettes or contents of the compartment 17, the upper cap 15 and body 10 are separated, the cap 15 being independently suspended by the suspension element 18 permitting the user to grasp the body 10 in one hand while the other hand is free to remove the cigarettes or other articles from the compartment 17. The cosmetic pencil 26 may be used by withdrawing the removable section 27 from the stationary or attached section 26 and of course it is obvious when the same is not in use that it will be concealed by the tassel 25.

I claim:

1. A carrying case comprising a receptacle body having an open upper end, a closure cap detachably connected with the upper end and defining with the body a compartment, a suspension means connected with the upper end of the closure cap for suspending the body from the arm of the wearer when the cap is attached thereto and for suspending

the cap from the arm of the wearer when separated from the body whereby to give the wearer free use of both hands to hold the body with one and to remove the contents with the other.

2. A carrying case comprising a receptacle body having an open upper end, a closure cap detachably connected with the upper end and defining with the body a compartment, 10 a suspension means connected with the upper end of the closure cap for suspending the body from the arm of the wearer when the cap is attached thereto and for suspending the cap from the arm of the wearer when 15 separated from the body whereby to give the wearer free use of both hands to hold the body with one and to remove the contents with the other, a boss at the lower end of the body, and a cup-shaped bottom section detachably connected with the boss and defining therewith a separate compartment.

3. A combined vanity and cigarette case, comprising a cylindrical body section having

an open upper end formed with an annular rabbeted and exteriorly threaded portion, 25 a removable closure cap having an interiorly threaded rabbeted portion adapted to fit over said end and defining with the body a cigarette-receiving compartment, suspension means connected with the upper end of the 30 cap for suspending the body from the arm of the wearer when attached to the cap and for suspending the cap from the arm of the wearer when separated from the body, whereby to give the wearer free use of both hands 35 to hold the body with one and to remove the contents with the other, a reduced exteriorly threaded depending boss at the lower end of the body, a mirror arranged in the upper end of the boss portion, and a cup-shaped bottom section having an interiorly threaded open upper end engageable over said boss to define a cosmetic compartment and to constitute means for covering the mirror when applied to the body.

SALVATORE QUENTIN LUPO.
